UNITED STATES PATENT OFFICE

ALONZO H. STARING, OF GERMAN FLATS, NEW YORK.

GATE.

SPECIFICATION forming part of Letters Patent No. 298,037, dated May 6, 1884.

Application filed November 21, 1883. (No model.)

To all whom it may concern:

Be it known that I, ALONZO H. STARING, a citizen of the United States, residing at German Flats, in the county of Herkimer and State of New York, have invented a new and useful Gate, of which the following is a specification, reference being had to the accompanying drawings.

My invention relates to gates, and more particularly to that class known as "farm-gates," the object being to provide a device of this character of cheap, simple, and durable construction, and one that shall be thoroughly effective in its operation.

15 The invention consists in the improved construction and combinations of parts hereinafter fully described, and pointed out in the claims.

In the drawings, Figure 1 is a perspective view of the gate partially closed. Fig. 2 is a 20 detail view of the latch mechanism.

A A' represent vertical standards, connected at their upper ends by a bar or cap, a, which is secured to said standards.

B represents a track, one end of which is mortised in the inner side of the standard A, and the other end of which is secured to the side of the standard A'. This track is shaped like an inverted letter V, flattened or elongated, it being highest at the center, and sloping from thence down to both ends, and it is provided with a face-rail, B', which is preferably constructed of round metal, although a track-rail consisting of a flat metal strap may be employed. To the outer sides of the standards

35 A A' are secured arms b b' b² b³, which are braced by cross-bars b⁴ b⁵. A short distance from the standard A is secured another upright or standard, A³, which supports one end of a track, C, of the same construction as the

40 track B, above described, the other end of said track C being secured to the side of the standard A' below the track B.

D represents the gate, which consists of a series of horizontal bars, E, secured between the strips forming the vertical uprights or bars F F' of the gate. The upright F consists of strips f f', between the upper ends of which is journaled a grooved wheel or caster, c, running upon the upper track, B, which is straddled or embraced by the strips f f', forming

the said upright F. The upright F' is constructed in a like manner of strips f² f², straddling the track C, and carrying a grooved wheel or caster, c', running upon said track.

At the lower end of the standard A' is secured 55 a strip or bar, G, having secured thereto vertical rods d, which serve to guide the lower portion of the gate. At the lower end of the upright A, and to the sides thereof, are secured strips e, projecting at right angles from the said upright. Said strips receive the end of the gate when it is closed, and serve to prevent the lateral movement of the same.

H represents weights interposed between the strips forming the vertical standards, which 65 facilitate the opening and closing of the gate after it has passed the central or raised portions of the tracks.

The inner side of the standard A is recessed to receive the roller journaled at the upper 70 end of the vertical upright F, in order that the gate may be entirely closed.

I represents the latch, which is pivoted between the strips f f', forming the upright F, and the body of which consists of a bell-crank 75 lever, the lower arm, i, of which is provided with a beveled catch or hook, i³, adapted to engage a mortise, i³, formed in the standard A. The other arm, i², is provided with a dog, i⁴, to limit the movement of the latch further than 80 to allow of its clearing and engaging the mortise.

The devices for opening and closing the gate are as follows:

At the ends of the arms b b' b² b³ are swiveled 85 pulleys j j' j² j³. Pulleys j⁴ j⁵ are also swiveled to the under side of the bar a, at about its center.

K K' represent cords secured at the upper end or arm, i², of the latch I, pivoted at the upper end of the vertical upright F. The cord K is passed through the pulley j⁴, and from thence through the pulley j. The cord K' is passed through the pulley j⁵, and from thence through the pulley j³. 90

L L' represent cords, which are connected, the cord L to the cord K, and the cord L' to the cord K', the cords L L' passing through the pulleys j' j², respectively.

95 The operation is as follows: When it is de- 100

sired to open the gate, either of the cords may be pulled with a quick pull, which will bring the gate to the other side of the raised portion of the tracks. It will then descend by gravity.

5 The closing of the gate is effected in the same manner.

In order to define more clearly the advantages and scope of my improvements, I would have it understood that I claim nothing shown 10 or described in Letters Patent No. 215,531, granted to W. W. McKay, May 20, 1879; but,

Having fully described my invention, what I claim as new, and desire to secure by Letters Patent, is—

15 1. In a gate, the combination, with the vertical uprights provided with tracks which are inclined or sloping from the center down to the end, of arms secured to the uprights A A' and having pulleys swiveled at their ends, a 20 bar connecting said uprights and having pulleys swiveled on its under side, a gate carrying rollers adapted to travel on said tracks, and cords secured to the upper arm, and a bell-crank latch pivoted to the upper end of the 25 upright F, the lower or horizontal arm of

which is provided with a hook or catch to engage a mortise in the adjacent gate-post, said cords passing through the pulleys on the under side of the bar *a*, and from thence through the pulleys on the ends of the arms *b b' b'' b'''*, as 30 set forth.

2. The combination, with a sliding gate having an upright, F, of a latch pivoted to the upper end of said upright, and consisting of a bell-crank lever, the upper arm of which has 35 a dog adapted to limit the movement of said latch by contact with the upper end of the upright F, and the lower arm of which has a catch engaging a mortise in the adjacent gate-post, and a cord connected to the upper arm of said 40 latch for raising the same from engagement with the notch *i*, substantially as set forth.

In testimony that I claim the foregoing as my own I have hereto affixed my signature in presence of two witnesses.

ALONZO H. STARING.
